Primary Examiner — Caron D Veynar*Assistant Examiner* — Mehri Bajoul(74) *Attorney, Agent, or Firm* — NSIP Law(57) **CLAIM**

We claim the ornamental design for a deodorizer for refrigerator, as shown and described.

DESCRIPTION

FIG. 1 is a front perspective view of a deodorizer for refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion of FIG. 1; and,

FIG. 10 is an enlarged view of the encircled portion of FIG. 2.

The broken lines in the figures show portions of the deodorizer for refrigerator which form no part of the claimed design. The dot-dash lines encircling portions of the claimed design that are illustrated in enlargements form no part of the claimed design.
